UNITED STATES PATENT OFFICE

ALBERT J. OTT AND CONRAD L. OTT, OF DETROIT, MICHIGAN, ASSIGNORS TO AMERICAN GRINDER COMPANY, OF DETROIT, MICHIGAN, A CORPORATION OF MICHIGAN

GEAR-GRINDING MACHINE

Application filed July 27, 1925. Serial No. 46,385.

The invention relates to an improved gear grinding machine of the generating type in which the gear is given a rolling motion relative to the grinding wheel by the simultaneous reciprocation and oscillation of the work carrying spindle. In general construction, our improved machine is similar to that described in our copending application Serial Number 615,583, filed January 29, 1923, which may be referred to for the underlying principles of generation. This application is directed primarily to certain improved features of construction which enhance the utility of the machine.

One of the objects of the invention is to provide a mechanism for adjusting the angularity of the grinding wheel spindle relative to the gear to be ground in order that both sides of the gear teeth may be generated without reversing the gear upon the work spindle. This feature is particularly advantageous when grinding stem gears and certain cluster gears for with this class of work it is often inconvenient and sometimes impossible to reverse the gear end for end in a grinding machine.

Another object is to provide means for adjusting the travel of the reciprocating carriage to adapt the same for various sizes of gears. Our improved travel adjustment regulates both the length of the stroke and also the position of the work spindle with respect to the grinding wheel.

A further object is to provide a grinding machine in which the wheel guard is mounted independently of the grinding wheel spindle and arranged to permit accessibility so that the wheel may be removed from its spindle without disturbing the guard. Our improved construction also permits the angular adjustment of the wheel spindle to grind either side of the gear teeth without corresponding adjustment of the wheel guard.

A still further object is the provision of an automatic stop mechanism whereby either the carriage alone may be stopped after the completion of a predetermined number of gear teeth or both the carriage and the grinding wheel may be simultaneously stopped. The automatic stopping of both the grinding

wheel and the work spindle is particularly desired upon the completion of the teeth of the gear because it is preferable to remove the ground gear and replace an unground gear while the grinding wheel is stationary.

Another object is the provision of an improved means for locating the work in proper relation to the grinding wheel.

Still further objects reside in other features of construction which are hereinafter more fully set forth.

In the drawings:—

Figure 1 is a perspective view of the improved machine looking toward the front and right side thereof;

Figure 2 is a fragmentary sectional front elevation showing the grinding wheel head and spindle;

Figure 3 is a transverse section on the line 3—3 of Figure 2;

Figure 4 is an elevation of the left side of the machine;

Figure 5 is a fragmentary side elevation showing the work spindle in section;

Figure 6 is a sectional plan view of the carriage bed with the carriage partly removed, this view also showing the automatic stop mechanism in sectional plan;

Figure 7 is a vertical section view looking from the rear of the machine and illustrating the driving mechanism for the carriage and the automatic stop mechanism;

Figure 8 is a rear view of the lower portion of the machine;

Figure 9 is an elevation of a portion of the right side of the machine showing portions of the carriage in section;

Figure 10 is a section on the line 10—10 of Figure 6;

Figure 12 is a diagrammatic front view showing the reversal of the grinding wheel;

Figure 13 illustrates in full lines the grinding wheel in position to grind the back side of the gear teeth, the dotted lines showing normal position;

Figure 14 is a perspective view showing the adjustment of the carriage travel.

In general, our machine comprises a base

A, on which a carriage B is longitudinally reciprocable. The carriage has transversely journaled therein a work spindle C adapted to receive the gear to be ground D at one end 5 thereof and provided at the opposite end with a tape drum E. Flexible tapes F are wrapped around the drum E to extend in opposite directions and are anchored upon an adjustable tape carriage G, the latter being carried by 10 ways H upon the base A. Between the tape drum E and the forward end of the work spindle C is an automatic indexing mechanism I adapted to index the gear D one tooth after each reciprocation of the carriage. The 15 indexing mechanism forms no part of the present invention, but is fully described in our copending application, Serial Number 31,152 filed May 8, 1925. A rotatable grinding wheel J is journaled upon the base and 20 arranged to be in operative relation to the gear D, the grinding wheel being preferably of relatively large diameter so that the entire width of the gear tooth may be ground without any lateral feed movement.

25 Referring now more particularly to the construction of the grinding wheel and its arrangement upon the machine, the base A is provided with the vertical ways 15 on which is vertically slidable the wheel carriage 16, the vertical adjustment being obtained by the adjusting screw 17 which engages a nut 18 attached to the carriage by the bracket 19. Swivelled on the carriage 16 is a swivel head 20 comprising an annular 30 housing 21 and the projecting hub portions 22. The wheel spindle 23 is journaled in suitable bearings 24 in the hub portions 22 and extends outward beyond the same for receiving the grinding wheel hub 25. Keyed 35 to the spindle within the housing 21 is a driving pulley 26 through which rotation is imparted to the spindle 23 by a suitable belt drive (not shown). The pulley 26 is arranged between the vertical ways 15 of the 40 base so that the belt drive may extend therebetween into engagement with the driving mechanism hereinafter more fully described.

45 In order to provide for the angular adjustment of the swivel head 20 an annular adjusting ring 27 is arranged between the swivel head and the carriage 16 and is firmly secured to the latter by means of bolts 28. The swivel head 20 is also secured to the ring by bolts 31 having heads 32 engaging an annular slot 30. Thus, when the bolts 31 are all tightened, the swivel head is positively secured to the carriage. The ring 27 has a portion of its outer periphery provided with gear teeth 33 and these teeth are engaged by a pinion 34 50 mounted on a shaft 35 extending parallel to the axis of the swivel head. The shaft 35 is journaled in a bearing 36 in a projecting portion 37 of the housing 21 and carries at its opposite end a worm wheel 38 adapted 55 to mesh with a worm 39 upon a vertical shaft

40, the latter being also journaled in the projecting portion of the housing. The upper end of the shaft 40 projects through the housing and is provided with a squared portion 41 which may be engaged by a suitable handle (not shown).

70 The grinding wheel 42 is attachable to the hub 25 by means of the annular clamp 43 and the clamping bolts 44. The wheel is conical at its outer periphery as indicated at 45 and has the grinding face 46 in a plane perpendicular to the spindle 23. In order to true the grinding surface 46 we have provided a truing mechanism arranged in a housing 47, the latter attached to the swivel 75 head 20 by the bracket arm 48 and secured thereto by bolts 49. A shaft 50 is journaled in the housing 47 parallel to the spindle 23 and carries at its outer end a swinging arm 51 provided with a diamond truing point 52. The arm 51 is adapted to be fed slowly across the face of the grinding wheel by means of a hand wheel 53 secured to a shaft 54 and connected to the shaft 50 by a reduction gearing. This gearing comprises a worm 55 upon the shaft 54 meshing with a worm wheel 56 upon a cross shaft 57, the latter carrying also a worm 58 adapted to mesh with the worm wheel 59 upon the shaft 50. Thus, by rotating the hand wheel 53 at a moderate speed, the diamond point 52 is moved very slowly across the grinding surface 46 resulting in a very accurate surface.

90 In order to provide for the wearing of the grinding surface, the wheel spindle 23 may be adjusted longitudinally in the swivel head 20 and as shown, this adjustment is accomplished as follows. The end of the spindle 23 opposite the grinding wheel carries a thrust collar 60 having the thrust bearings 61 and 62 mounted upon opposite sides thereof. 95 63 is a thrust housing having the inwardly projecting flanges 64 and 65 engageable with the respective thrust bearings. This housing is secured to a feed screw 66 having peripheral threads 67 engageable with the feed nut 68. A thrust flange 69 on the feed nut engages the shoulders 70 upon the feed housing 71, the latter being secured to the hubs 22 of the 100 swivel head by the bolts 72. The feed nut 68 has secured thereto by the bolts 73 a feed gear 74 having peripheral teeth 75. 76 is a hand wheel rotatably mounted upon the said housing 71 and having pivotally mounted thereon the feed pawl 77 normally held in engagement with the teeth 75 by a spring pressed 105 plunger 78 bearing against the upper arm 79 of the pawl. With the construction as above described, the longitudinal adjustment of the grinding wheel may be effected by rotation of the hand wheel 76 thereby moving the wheel spindle 23 within the swivel head 20.

110 The normal position of the grinding wheel is illustrated by the full lines in Figure 12 and shows the plane of the grinding face in- 115

clined an amount corresponding to the pressure angle of the tooth to be ground. When in this position the carriage 16 is at the upper end of the vertical ways 15 and the wheel spindle 23 points downwardly. When it is desired to grind the opposite side of the gear teeth without reversing the gear end for end, the grinding wheel is arranged in the position shown in dotted lines in Figure 12. In order to effect this adjustment the carriage 16 is lowered on the vertical ways 15 and the swivel head 20 is adjusted to incline the wheel spindle upwardly so that the plane of the grinding wheel assumes an inclination in the opposite direction equal to the pressure angle of the gear. The grinding wheel is removed from the hub 25 by loosening the clamp 43, reversed and replaced upon the hub with the grinding face on the opposite side. For angularly adjusting the swivel head 20 the bolts 31 are first loosened and the rotation of the housing 21 effected by rotating the shaft 40. Since the pinion 34 is in mesh with the gear teeth 33 upon the ring 27 and since this ring is secured to the carriage 16 the turning of the shaft 40 will rotatably adjust the housing 21 to the degree desired. Figure 13 illustrates the engagement of the grinding wheel with the gear tooth, the full lines indicating the wheel in a position to grind the coast side of the tooth and the dotted lines indicating the wheel in position for grinding the driving side of the tooth. It should be noted that the plane of the grinding face corresponds with the sides of an imaginary rack adapted to mesh with the gear.

It is the usual practice to provide grinding wheels with a wheel guard mounted upon the wheel spindle and surrounding the wheel itself. Such a construction is undesirable in our grinding machine because it would require that the wheel guard be removed each time the wheel were reversed for grinding the opposite sides of the gear teeth. We have therefore, provided a different construction in which the wheel guard is mounted upon the base of the machine and is of sufficient size to permit the angular adjustment of the grinding wheel within the same without adjustment of the housing. Thus, as shown in Figures 1 and 4, the base A is provided with an upwardly extending front housing 80 and at the left side with a side plate 81. The latter has hingedly connected thereto by the hinges 82 a door 83 of sufficient size to permit removal of the grinding wheel from the housing when the door is swung outwardly. The top of the door has hingedly connected thereto a water guard 84 which, as shown, is closed upon the top, front and left sides. The water guard is arranged to enclose the space adjacent the gear while the grinding is taking place, but is adapted to be swung back upon the hinges 85 to remove the gear. For retaining the water guard in any position of

adjustment, the following construction is used. A collar 86 is secured to one of the hinges 85 and is provided with teeth 87. A similar collar 88 is keyed to the pivot rod 89 and has corresponding teeth 90 engageable with said first-mentioned teeth. A spring 91 is sleeved upon the rod 89 between the collar 88 and an abutment 92. The arrangement is such that the water guard is normally held in adjusted position by the engagement of the teeth, but upon manual adjustment by means of the handle 93 relative movement of the collars 86 and 88 is permitted. With the housing construction as above described, it will be apparent that the door 83 and water guard 84 may be swung outward as a unit when removing the grinding wheel. Furthermore, the housing construction is such that angular adjustment of the wheel is permitted independently of the housing.

Our machine is driven from a horizontal shaft 94 at the rear of the machine through the pulley 95 which may be connected to an outside power source. A clutch 96 connects the wheel pulley 95 to the shaft 94 and is operated by a shifting fork 97. 98 is the driving pulley for the grinder wheel and is in alignment with the pulley 26 upon the spindle 23 and is connected thereto by a suitable belt (not shown). 99 is a carriage drive pulley adapted to be connected to a driven pulley 100 upon a countershaft 101 arranged beneath the carriage B. A clutch collar 102 is longitudinally movable upon the shaft by means of a shifting arm 103 and carries the clutch teeth 104 adapted to engage corresponding clutch teeth 105 on the pulley 100. The shaft 101 is connected to the cam drum shaft 106 by suitable reduction gearing which as shown, comprises the pinion 107, idler gear 108, idler pinion 109 and drive shaft gear 110. The cam drum shaft 106 is arranged beneath the carriage bed 111 and has secured thereto, the drum cam 112, the latter being provided with a cam slot 113 in which a roller 114 is inserted. The roller is carried by a pin 115 depending from an oscillating lever 116 pivoted at 117 to the bed of the machine. The arrangement is such that upon rotation of the cam drum 112 the lever 116 is given an oscillatory motion. A block 118 is longitudinally slidable in a slot 119 in the lever and has a pin 120 projecting upwardly therefrom and engaging a transverse slot 121 in a cross member 122. The latter is adapted to be clamped to the carriage B by means of the clamping strips 123 and the bolts 124. For securing the pin 120 to the cross member 122, the upper end is threaded at 125 for receiving a clamping nut 126. Thus, by loosening the nut the block 118 may be adjusted toward or away from the pivot 117 of the lever 119 and in this manner the stroke of the carriage may be varied.

It is also desirable to provide for a longi-

tudinal adjustment of the carriage B relative to the grinder wheel in order to compensate for the change in horizontal location of the grinder wheel when mounted for grinding the opposite sides of the gear teeth. Thus 5 as clearly illustrated in Figure 12, when the angular adjustment of the grinder wheel 42 is effected from the position shown in full lines to that shown in dotted lines, the working portion of the grinder wheel is displaced horizontally and a corresponding adjustment of the normal position of the carriage is required so that the gear may be brought into 10 operative relation to the grinder wheel in its new position. This adjustment may be accomplished by removing the bolts 124 from the carriage B, thereby disengaging the cross member 122 from the carriage. The carriage is then moved horizontally on the ways 111 15 for the required distance and at the same time the adjustable tape carriage G is correspondingly moved on the ways H. The carriage B is then again secured to the cross member 122 by means of the clamping strips 123 and the bolts 124, the latter being inserted in the 20 apertures 124^a, which are provided in the proper location on the carriage B. The tape carriage G is also secured in adjusted position to the ways H by means of suitable 25 clamping means which, as shown, comprises the clamping bolt G'.

As before stated one of the objects of our invention is to provide an automatic stop mechanism which will stop either the carriage alone or the carriage and the grinding wheel. For accomplishing this result, we have provided the following mechanism. Rising upwardly from the base A is a housing 128 for the automatic stop mechanism which supports a horizontal shaft 129. A 30 ratchet wheel 130 is journaled upon the shaft 129 and a ratchet lever 130' also rotatably mounted on said shaft carries a lateral arm 131 projecting into the path of the carriage B. The end of the arm 131 is provided with a finger 132 having an inclined face 133 adapted to be engaged by the actuating member 134 on the carriage. 35

The ratchet lever 130' has pivotally mounted thereon a ratchet pawl 135 held in engagement with the teeth of the ratchet wheel by the spring pressed plunger 136. The arrangement is such that at each reciprocation of the carriage B the actuating member 134 40 striking the ratchet finger 132 rotates the ratchet lever 130' and consequently moves the ratchet wheel one tooth. A spring pressed stop pawl 137 is mounted in the housing 128 and prevents the rotation of the 45 ratchet wheel in the opposite direction. 138 is a dial journaled upon the shaft 129 and provided with graduations upon the outer surface thereof. This dial carries an inwardly extending arm 139 in which is slidably 50 mounted a pin 140 having a handle 141 at one

end thereof and a cam 142 at the opposite end. The cam is provided with teeth 143 adapted to engage the teeth of the ratchet wheel and is normally held in engagement therewith by the spring 144. The arrangement is such that 70 by withdrawing the handle 141, the cam may be set in any predetermined position with respect to the ratchet wheel and preferably the position selected is determined by the fixed pointer 145. The graduations upon the dial 75 138 correspond to the maximum number of teeth which can be ground before the automatic stop takes place.

A horizontal shaft 146 is arranged adjacent the housing 128 and has rockably mounted thereon two trips 147 and 148 respectively. The trip 147 has a cam 149 projecting into the path of the cam 142 and arranged to be actuated thereby upon a predetermined movement of the ratchet wheel. The trip 147 80 is keyed or otherwise secured to the shaft 146 and at the outer end of the latter is arranged a handle 150 by which the trip 147 may be manually rocked. A pin 151 in the upper portion of the trip 147 is manually adjustable by means of a transverse pin 152 to engage a recess 153 in the adjacent trip 148 thereby locking both trips together. The pin 152 is slidable through the slot 154 and may be held in either position of adjustment by 85 laterally moving the same into the recesses 155 and 156. The trip 147 has the lug 157 projecting therefrom normally held in the path of the carriage clutch release arm 158 by means of a spring pressed plunger 159 90 bearing against the under surface of the trip. This clutch release arm is secured to a vertical tube 160, and is rockable by means of a handle 161 so that the projecting cam lug 162 may ride under the lug 157 and engage 95 100 behind the same. The tube 160 is provided with a rock arm 163 to which is fastened one end of a link 183, the other end of the link being connected to a rock arm 184, is also connected by a link 186 to an arm 187 of the 105 rockable member 188, the latter carrying also the shifting arm 103 which, in turn, has a roller 189 engaging the clutch collar 102. A 110 spring 164 is secured to the rock arm 184 and anchored to the frame of the machine, this arrangement providing resilient means for urging the clutch out of engagement. For engaging the clutch to start the carriage the handle 161 is rocked clockwise, thereby causing 115 projecting lug 157 to ride over cam lug 120 162 until it is in front of the same, when the pressure of the spring pressed plunger 159 causes the lug 157 to drop in front of the cam lug forming a stop to prevent return movement of the release arm and thereby hold the 125 clutch engaged.

The mechanism for stopping both the carriage and the grinding wheel comprises a rod 165 arranged within the tube 160 and secured at its upper end to the release arm 166. 130

The latter is arranged directly above the carriage release arm 158 and is provided with a cam lug 167 adapted to engage behind the projecting lug 168 of the trip 148. The lower end of the rod 165 has a rock arm 169 connected by a link 170 to a second rock arm 171, the latter being pivoted at 172 adjacent the clutch 96. For normally holding the clutch 96 disengaged, a spring 173 is sleeved upon the link 170 between the collar 174 and a fixed abutment 175. For engaging the clutch 96, the release arm 166 is rocked clockwise by a handle 176 until the lug 168 drops in front of the cam lug 167. For releasing the clutch 15 the trip 148 must be rocked to withdraw the projecting lug 168 from the cam lug 167. To accomplish this purpose, it is necessary to lock the trip 148 to the trip 147 by laterally moving the pin 151 into the recess 153. Both 20 clutches are now released either by the handle 150 or by the engagement of the cam 142 with cam 149.

The operation of the automatic stop mechanism as above described, is as follows. The 25 handle 141 is first pulled outwardly to release the cam 142 from the ratchet wheel and the dial 138 is then rotated until the graduation indicating the number of teeth on the gear to be ground is opposite the pointer 145. 30 The handle 141 is then released thus locking the cam 142 to the ratchet wheel. The machine is then started by operating the handles 176 and 161 and at each reciprocation of the carriage a gear tooth is ground and 35 at the same time the ratchet wheel is advanced one tooth. When the last tooth has been ground the cam 142 striking the cam 149 of the trip mechanism releases the trips and disengages the clutches.

40 When setting up the grinding machine for a particular gear, it is necessary that the gear be angularly adjusted on the work spindle C to correspond with the setting of the grinder wheel. In order to provide a rapid 45 means for properly adjusting the gear, we have provided the arbor with a collar 177 adjustably clamped thereon by suitable means such as the set screw 178. This collar has a slot 179 extending longitudinally there- 50 of in which may be inserted a knife blade 180. The latter has an arm 181 projecting outwardly therefrom into registration with the gear to be ground. The knife blade 180 is inserted in the slot and the gear D rotated 55 upon the arbor until it contacts with the projecting arm 181, after which, the gear is clamped upon the arbor by suitable clamping means such as the nut and washer 182.

What we claim as our invention is:—

60 1. In a gear grinding machine, a reciprocating carriage, an oscillating work spindle thereon adapted to carry the gear to be ground, a grinding wheel below said work spindle having a plane face, a wheel spindle 65 extending perpendicularly to said face, and

means for adjustably mounting said wheel spindle on said base, whereby the plane of said face is inclined alternatively in opposite directions corresponding to the pressure angle of said gear.

2. In a gear grinding machine, the combination with a base or frame having a vertically adjustable slide thereon, a ring secured to said slide having teeth thereon, a wheel head rotatably mounted on said slide, a wheel spindle journaled in said wheel head, a grinding wheel on said wheel spindle, a shaft in said wheel head having a pinion thereon meshing with the teeth on said ring, means for rotating said shaft whereby said wheel head is angularly adjusted, and means for clamping said wheel head to said slide.

3. In a gear grinding machine, the combination with a base, of a rotatable grinding wheel journaled thereon, a carriage reciprocable on said base, a work spindle on said carriage, means for oscillating said work spindle in timed relation to the reciprocation of said carriage, means actuated intermittently at each reciprocation of said carriage, a common driving means for said grinding wheel and said carriage, a clutch controlling both said grinding wheel and carriage, a second clutch controlling only said carriage, means actuated after a predetermined number of reciprocations of said carriage for disengaging one of said clutches, and means cooperating with said first mentioned means to simultaneously disengage said second clutch.

4. In a gear grinding machine, the combination with a reciprocating carriage, an oscillating spindle thereon adapted to carry the gear to be ground, a grinding wheel adapted to be engaged by said gear during the reciprocation of said carriage, driving means for said carriage and grinding wheel, a clutch controlling both said carriage and grinding wheel, a second clutch controlling only said carriage, ratchet mechanism operated by each reciprocation of said carriage, a pair of trips normally holding the respective clutches engaged, means for automatically releasing one of said trips after a predetermined movement of said ratchet mechanism, and means for connecting the second trip to said first trip whereby both are simultaneously actuated.

5. In a gear grinding machine, the combination with a grinding wheel, of a work spindle, means for clamping a gear on said spindle, means for oscillating and reciprocating said work spindle to impart a rolling motion to said gear relative to said grinding wheel, a rotatably adjustable collar on said spindle, said collar having an open-sided longitudinal slot therein, a knife gauge having a portion for removably engaging said slot, and a finger on said knife gauge adapted to contact with a tooth of said gear.

6. In a gear grinding machine, the com-

bination with a frame and a reciprocable carriage, of a cam drum journaled in said frame, an oscillating lever pivoted to said frame, a transverse pin on said lever engaging said cam drum, a member connecting said lever and said carriage for reciprocating the latter, and means for adjusting said member toward and away from the pivot of said lever to vary the stroke of said carriage.

7. In a gear grinding machine, the combination with a frame and a reciprocable carriage, of a cam drum journaled in said frame, an oscillating lever pivoted to said frame, a transverse pin on said lever engaging said cam drum, a pin projecting upwardly from said lever, a cross member secured to said pin, means for clamping said cross member to said carriage, and means for longitudinally adjusting said carriage when said cross member is unclamped.

8. In a gear grinding machine, the combination with a frame and a reciprocating carriage, of a cam drum journaled in said frame, an oscillating lever pivoted to said frame, a transverse pin on said lever engaging said cam drum, said lever having longitudinal guide ways therein, a block sliding in said guide ways, a transversely slotted cross member, a pin extending from said block through the slot in said cross member, means for clamping said pin to said cross member, means for clamping said cross member to said carriage, and means for longitudinally adjusting said carriage when said cross member is unclamped.

9. In a gear grinding machine, the combination of means for supporting a gear, a rotatable grinding wheel having a face for engaging a tooth surface of said gear, means for angularly adjusting said grinding wheel so that said face is inclined alternatively on opposite sides of a vertical plane an amount corresponding to the pressure angle of the gear teeth.

10. In a gear grinding machine, the combination of a rotatable grinding wheel having a working face for engaging a gear tooth, a gear-supporting arbor, means for imparting a rolling motion to the gear on said arbor relative to said grinding wheel, means for angularly adjusting said grinding wheel to incline the working face thereof to the pressure angle of the gear alternatively on opposite sides of the center line of the gear, and means for adjusting the relation of said grinding wheel and said gear-supporting arbor in transverse directions, whereby the working face of said grinding wheel is in operative relation alternatively to the opposite sides of the gear teeth.

11. In a gear grinding machine, the combination of a rotatable grinding wheel having a working face transverse to the axis of rotation, a gear-supporting arbor, means for reciprocating and oscillating said arbor to

impart a rolling motion to the gear relative to said grinding wheel, means for angularly adjusting said grinding wheel to incline the working face thereof to the pressure angle of the gear alternatively on opposite sides of the center line of the gear, means for adjusting said grinding wheel in a direction transverse to the line of rolling of said gear, and means for adjusting said gear-carrying arbor in the direction of said line of rolling.

12. In a gear grinding machine, the combination of a base, a head swivelled on said base, a rotatable grinding wheel journaled in said head having a working face transverse to the axis of rotation, means for supporting a gear in operative relation to said grinder wheel, means for imparting a rolling motion to said gear relative to said grinder wheel, means for angularly adjusting said swivelled head to alternatively incline the face of said wheel to the pressure angle of the gear teeth on opposite sides of the center line of the gear, and a guard housing surrounding said grinding wheel and secured to said base independently thereof, said housing having clearance permitting the aforesaid angular adjustment.

13. In a gear grinding machine, the combination of a base, a wheel head swivelled on said base, a rotatable grinding wheel journaled in said head having a working face extending transverse to the axis of rotation thereof, a carriage reciprocable on said base in a substantially horizontal plane, a gear-carrying arbor journaled in said carriage, means for reciprocating said carriage and oscillating said arbor to impart a rolling motion to said gear, means for adjusting said wheel head to incline said working face alternatively on opposite sides of a vertical plane, whereby opposite sides of the gear teeth may be ground, means for vertically adjusting said wheel head on said base, and means for horizontally adjusting the normal position of said carriage on said base, said vertical and horizontal adjustments being adapted to compensate for the displacement of said grinding wheel in its opposite positions of angular adjustment.

14. In a gear grinding machine, the combination with a base, of a head swivelled on said base, an arbor journaled in said head, a grinding wheel having a working face in a plane perpendicular to said arbor, means for mounting said grinding wheel on said arbor with its working face arranged alternatively on opposite sides, means for angularly adjusting said swivelled head to incline the working face of said grinding wheel alternatively on opposite sides of a vertical plane, a carriage horizontally reciprocable on said base, a gear-carrying arbor rotatable in said carriage and adapted to support a gear above said grinding wheel, means for reciprocating said carriage and oscillating

5 said arbor to impart a rolling motion to said gear, means for horizontally adjusting said carriage to bring said gear-carrying arbor into operative relation to said grinding wheel when the latter is in either of the aforesaid positions of inclination, and means for vertically adjusting said swivelled head.

10 15. In a gear grinding machine, the combination with a base, a ring secured to said base, a wheel head rotatably mounted on said ring, a grinding wheel journaled in said wheel head, said ring having teeth formed in a portion thereof, a shaft in said wheel head having a pinion thereon meshing with the teeth on said ring, and means for rotating said pinion to angularly adjust said wheel head.

20 25 30 16. In a gear grinding machine, the combination with a base, of a rotatable grinding wheel journaled thereon, a carriage reciprocable on said base, a work spindle journaled on said carriage, means for reciprocating said carriage and oscillating said work spindle in timed relation to impart a rolling motion to said work spindle, means for rotating said grinding wheel, means actuated by a predetermined number of reciprocations of said carriage for automatically stopping the movement of said carriage, means for stopping the rotation of said grinding wheel, and manually operable means for connecting said wheel stopping means to said carriage stopping means whereby the former is automatically operable with the latter.

35 40 45 50 55 17. In a gear grinding machine, the combination with a base, of a rotatable grinding wheel journaled thereon, means for rotating said grinding wheel, a carriage reciprocable on said base, a work spindle journaled on said carriage, means for reciprocating said carriage and oscillating said work spindle in timed relation to impart a rolling motion to the work relative to said grinding wheel, a clutch controlling both the rotation of said grinding wheel and the reciprocation of said carriage, a second clutch controlling said carriage only, means actuated for a predetermined number of reciprocations of said carriage for automatically disengaging the second mentioned clutch, manually operable means for controlling the first mentioned clutch, and means for connecting said manually operable means to said automatically operable means to automatically operate the former with the latter.

60 65 18. In a gear grinding machine, the combination with a frame and a reciprocable carriage, of a cam journaled in said frame, an oscillating lever pivoted to said frame, having a cam follower portion engaging said cam, a member connecting said lever and said carriage for reciprocating the latter and means for adjusting said member toward and away from the pivot of said lever to vary the stroke of said carriage.

19. In a gear grinding machine, the combination of a rotatable grinder wheel having a working face for engaging a gear tooth, a gear-supporting arbor arranged above said grinding wheel and means for angularly adjusting said grinding wheel to incline the working face thereof to the pressure angle of the gear alternatively on opposite sides of the center line of the gear.

70 75 80 85 90 20. In a gear grinding machine, the combination of a rotatable grinding wheel having a working face for engaging a gear tooth, a gear-supporting arbor arranged above said grinding wheel, means for imparting a rolling motion to the gear-carrying arbor relative to said grinding wheel, means for angularly adjusting the grinding wheel to incline the working face thereof to the pressure angle of the gear alternatively on opposite sides of the center line of the gear and means for adjusting the relation of said grinding wheel and said gear-supporting arbor in transverse directions for sufficient distances to enable the working face of said grinding wheel to alternatively engage the opposite sides of the gear teeth.

In testimony whereof we affix our signatures.

ALBERT J. OTT.
